UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,094, dated September 22, 1896.

Application filed August 5, 1896. Serial No. 601,829. Term of patent 3½ years.

To all whom it may concern.

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10. The design consists of groups of flowers and leaves of the carnation arranged between vertical ornamental stripes with a line of flowers through the center of said stripes and a background of small fleur-de-lis-shaped ornaments between said stripes and groups of flowers and leaves, as represented in the accompanying drawing.

15. The border for said design consists of similar groups of flowers and leaves of the carnation arranged in ornamental panels with small 20 fleur-de-lis-shaped ornaments forming a background between said panels and light vertical lines above and beneath said panels, and below said vertical lines is a horizontal band formed of ornamental scrolls with flowers 25 through the center, as shown in the drawing.

What I claim is—

1. The design for wall-paper herein shown and described.
2. In the design for wall-paper, the border 30 herein shown and described.

Witness my hand this 1st day of August, 1896.

CHARLES BOOZ.
